UNITED STATES PATENT OFFICE.

EMERY PAPP, OF CLEVELAND, OHIO, ASSIGNOR OF ONE-HALF TO NICHOLAS PAPP,
OF CLEVELAND, OHIO.

DESIGN FOR A LAMP-STAND.

56,886.

Specification for Design.

Patented Jan. 4, 1921.

Application filed July 9, 1920. Serial No. 395,158. Term of patent 7 years.

To all whom it may concern:

Be it known that I, EMERY PAPP, a subject of the Hungarian Government, (who have declared my intention of becoming a citizen of the United States), and residing at Cleveland, in the county of Cuyahoga and State of Ohio, have invented a new, original, and ornamental Design for a Lamp-Stand, of which the following is a specification,

reference being had to the accompanying drawings, forming part thereof.

The figure, which is divided or broken for clearness of illustration, is a front elevation of a lamp stand showing my new design.

I claim:

The ornamental design for a lamp stand, as shown.

EMERY PAPP.
